NARROW WOVEN FABRIC

Charles S. Wackerman, Bridgeport, Conn., assignor to The American Fabrics Company, Bridgeport, Conn.

Application August 27, 1949, Serial No. 4,736

Term of patent 7 years

(Cl. D92—1)

To all whom it may concern:

Be it known that I, Charles S. Wackerman, a citizen of the United States, residing at Bridgeport, in the county of Fairfield, State of Connecticut, have invented a new, original, and ornamental Design for a Narrow Woven Fabric, of which the following is a specification, reference being had to the accompanying drawing, forming part hereof.

The drawing shows a face view of a piece of narrow woven fabric embodying my design. The background of the narrow woven fabric is partially omitted for convenience in illustration.

I claim:

The ornamental design for a narrow woven fabric, substantially as shown and described.

CHARLES S. WACKERMAN.
